[57] CLAIM

The ornamental design for a bottle, as shown and described.

DESCRIPTION

FIG. 1 is a perspective view of a bottle showing my new design;

FIG. 2 is a front elevational view thereof;

FIG. 3 is a side elevational view thereof, the opposite side being a mirror image thereof;

FIG. 4 is a rear elevational view thereof;

FIG. 5 is a top view thereof;

FIG. 6 is a bottom view thereof;

FIG. 7 is a perspective view of a modification of the bottle of my new design;

FIG. 8 is a front elevational view of FIG. 7;

FIG. 9 is a side elevational view of FIG. 7, the opposite side being a mirror image thereof;

FIG. 10 is a top view of FIG. 7; and

FIG. 11 is a bottom view of FIG. 7.
